GARMENT PLACKET

Eugene Pedatella, New York, N. Y.

Application May 18, 1942, Serial No. 443,347

2 Claims. (Cl. 2—74)

This invention relates generally to garments, but more specifically to expandable means associated with ladies dresses to serve as a substitute for placket openings with fastenings therefor at the waist portion.

The main object of the invention resides in the provision of a concealed and detachably fastened plait joining the edges of a placket opening at the waist portion of a dress and serving to expand the girth of the garment when applied to and removed from the wearer.

Another object of the invention resides in the production of a ladies garment wherein provision is made for the expansion thereof at the waistline without the formation of a placket opening.

A further object of the invention is to produce a garment of the above character wherein the expandable portion normally lies flat when fastened by concealed fastening members, said fastening members being non-metallic and non-corrosive to perspiration, washing and cleaning.

Further objects lie in the economy of application of the expandable device to a garment and in the efficiency of operation.

These objects and other incidental ends and advantages of the invention will hereinafter appear in the progress of the disclosure and as pointed out in the appended claims.

Accompanying this specification is a drawing showing a preferred form of the invention wherein corresponding reference characters designate corresponding parts throughout the several views, and wherein:

Figure 1 is a front view in perspective of a dress showing the expandable device at the waist portion in closed position.

Figure 2 is a partial front view in elevation of the expandable device with portions broken away.

Figure 3 is a transverse sectional view of the device in expanded position.

Figure 4 is a similar view showing the device in section while in closed position, being taken along the plane 4—4 of Figure 2.

In accordance with the invention and the preferred form shown, a garment such as A is provided with conventional panels 10 and 19, the panels adjacent the waistline and at the placket region being provided with extensions to form a plait concealed by a double flap as best shown in Figures 2 and 4. Thus, panels 10 and 19 above and below the placket region each have conventional upper and lower vertical edges indicated by numerals 13c and 13d respectively, said edges being secured together by means of vertical lines of stitching 20c and 20d. Panel extensions be-

tween lines of stitching 20c and 20d are provided to form an extensible concealed plait and cooperating flaps as hereafter described.

Panel 10 is provided with an extension 10a proceeding inwardly from a point indicated by the arrow line 10b, the inner edge 13 of said extension being secured as by a line of stitching 12 to the inner edge 13' of an extension portion 11 forming part of a second extension 19a proceeding from panel 19 at a point indicated by the arrow line 19b. Points 10b and 19b would normally indicate the position of the placket edges in a conventional placket opening, and it is understood that it is feasible to join separate extensions of any desired material to the panels 10 and 19 by conventional vertical lines of stitching instead of the use of integral extensions as described.

Extension 19a is provided with a plurality of folds to form a double flap with extension portion 11 and panel 19. Thus between extension portion 11 and point 19b, extension 19a is folded outwardly and inwardly upon itself to form the bight 14 and an outer wall 15, and then folded again in the opposite direction to form a bight 16 and an underwall 17, the latter superposing a part of panel portion 19 and joining the same at bight 18. By referring to Figure 4, bights 14 and 18 form the outer edges of two two-ply flaps, the said flaps being joined at the inner end by bight 16. The lower flap formed by walls 15 and a portion of wall 11 is provided with a series of spaced buttonholes 21 along the length thereof, the said buttonholes securing said walls together by the buttonhole stitching 21a, while wall 17 adjacent bight 16 is secured to panel 19 by means of a vertical line of stitching 20, the wall 17 and a portion of panel 19 forming the outer flap. Adapted to engage buttonholes 21 are buttons 22 secured to the outer side of extension 10a as by stitching 22a.

It is to be observed that by folding back the outer flap formed from wall 17 and panel 19, buttons 22 may be engaged and disengaged from buttonholes 21 by hand manipulation. During disengagement opposite tension between panels 10 and 19 induced by the application and removal of a dress will bring about an opening of the plait formed between extension 10a and extension portion 11 as best shown in Figure 3. This extension is prevented from taking place when the fastening members are in engaging position as during normal wear of the garment.

Extensions 10a and 19b have upper and lower transverse edges each indicated by numerals 13a

and 13b, these edges being secured together by lines of stitching 12a and 12b, respectively. Lines of stitching 12a and 12b as shown join the vertical lines of stitching 20c and 20d while the transverse edges 13a and 13b join the vertical edges 13c and 13d of the panel members 10 and 19. A pair of parallel and spaced diagonal lines of stitching 20a and 20b are adapted to secure together the extensions 10a and 19a at the upper and lower regions thereof, said lines of stitching joining the vertical lines of stitching 20c and 20d.

Thus, a placket is provided which may be applied to any portion of a garment wherein concealed fastening means are provided and permitting extension of a concealed plait for extending the girth of the garment during application and removal thereof from a wearer.

I wish it understood that minor changes and variations in the material, location and integration of parts may all be resorted to without departing from the spirit of the invention and the scope of the appended claims.

I claim:

1. In a dress, a placket between the panel members and across the waistline comprising an expansible plait, a pair of superposed flap members concealing said plait and being connected together adjacent the inner edges, the said plait and flap members being formed from extensions of the placket edges of the panel members, and detachable fastening means between the inner flap member and the plait to render said plait openable and closeable.

2. In a dress, a placket between the panel members and across the waistline comprising an expansible plait, a pair of superposed flap members concealing said plait and being connected together adjacent the inner edges, the said plait and flap members being formed from extensions of the placket edges of the panel members, and concealed means to render said plait openable and closeable.

EUGENE PEDATELLA.
